UNITED STATES PATENT OFFICE.

JOSEPH YARTIN, OF NEW YORK, N. Y.

TOBACCO-PIPE.

1,240,399.

Specification of Letters Patent. Patented Sept. 18, 1917.

Application filed June 22, 1915. Serial No. 35,558.

To all whom it may concern:

Be it known that I, JOSEPH YARTIN, a subject of the Emperor of Austria-Hungary, residing at New York city, in the county of New York and State of New York, have invented certain new and useful Improvements in Tobacco Pipes, of which the following is a specification.

My invention relates to certain new and useful improvements in tobacco pipes and has as a primary object the provision of a device of this character which may be used as a cigar holder or as a tobacco pipe.

Another object of the invention is to construct the same that the parts thereof may be quickly and readily removed to facilitate cleaning.

A further object of the invention is to provide a device of the character described which when placed upon a table or similar object will remain in an upright position.

With the above and other objects in view my invention resides preferably in the construction, combination, and arrangement of parts as hereinafter set forth in the specification and illustrated in the accompanying drawings, in which—

Figure 1 is a longitudinal sectional view of my invention showing the same assembled for use as a tobacco pipe.

Fig. 2 is a top plan view of my invention showing the same assembled for use as a cigar holder.

Fig. 3 is a side elevation of the same partly in section, showing the invention assembled for use as a cigar holder.

Similar reference characters indicate similar parts throughout the various views of the drawings.

Referring more particularly to the drawings in which the preferred embodiment of my invention is illustrated, I provide a stem 1 having the usual mouth-piece 2 threaded at 3 thereon. The stem 1 is slightly modified to facilitate its use as a tobacco pipe stem or a cigar holder. The stem and mouth-piece are provided with the usual central duct designated 4, said duct 4 extending throughout the length of the stem 1 and opening at both ends thereof. The end of the duct 4 remote from the mouth-piece 2 is countersunk or enlarged as indicated at 5 for a purpose which will hereinafter appear.

For use as a tobacco pipe the stem is pro-

vided with an enlarged portion 6 at any point throughout its length but preferably adjacent the portion of the stem remote from the mouth-piece 2. The enlarged portion 6 is provided with a relatively large threaded aperture 7 communicating with the central duct 4 for a purpose which will hereinafter appear. A closing end cap 8 is provided, said end cap 8 being threaded both interiorly and exteriorly for a purpose which will hereinafter appear, it being apparent that the free extremity of the stem 1 is threaded as at 9 to receive the internally threaded portion of the cap 8, as shown to advantage in Fig. 1. The cap 8 is permanently associated with the stem 1 by means of a flexible element, in this instance a chain 10.

For use as a tobacco pipe, I provide a modified bowl 11 having a relatively large opening 12 in the bottom 13 thereof and a longitudinally extending shank 14 for reception in the threaded opening 7, as shown to advantage in Fig. 1. The distance to which the bowl 11 is receivable into the aperture 11 is limited by the bottom 13. The bowl 11 is provided with a supplemental removable bottom 15, said bottom being perforated as at 16 and provided with spaced laterally extending resilient arms 17, the free extremities of the arms 17 being bent angularly as at 18 for engagement over the lower extremity of the threaded shank 14, said arms being receivable in the opening 12. This structure facilitates the removal of the perforated bottom 15 for cleaning purposes. As shown to advantage in Fig. 1, the device of my invention may be used as a tobacco pipe.

For use as a cigar holder, attention is directed to Figs. 2 and 3. The bowl is removed from the opening 7 and the cap 8 is removed from the threaded extremity of the stem 1. This cap is now inserted in the opening 7 and threaded thereinto as indicated at 19. The cigar, cigarette, or the like may be inserted in the countersunk portion 5 of the central duct 4 and the device is ready for use as a cigar or cigarette holder.

For cleaning the parts may be readily disassembled, the supplemental bottom 15 of the bowl 11 being readily removed for cleaning and the central duct 4, by virtue of the extension of the same throughout the length

105

110

of the stem 1, facilitating the insertion of a cleaning rod and rendering more effective the cleaning operation.

It will be noted that the enlarged portion 6 extends flush with the round face of the stem 1 at the bottom and is flat so that the pipe may be readily placed upon an object in an upright position. It is to be understood that the enlargement 6 need not be of 10 the configuration shown but may be formed with any fancy design desired. In actual practice the peculiar manner in which the perforated bottom 15 is secured in the bowl 11 may be modified, as well as the construction of the threaded cap 8.

While I have shown and described my invention as possessing a peculiar form and construction, it is desired that it be understood that I may make such changes in the 20 details thereof that do not depart from the spirit and scope of the invention as claimed.

Having thus described my invention what I claim and desire to secure by Letters Patent is:

25 1. A tobacco pipe, including a stem having a central duct extending throughout its length, one end of said stem around said

central duct being countersunk, an end cap threaded internally, said stem having an enlarged portion, said enlarged portion having a laterally extending threaded opening 30 therein communicating with the central duct, and a tobacco bowl threaded in said opening and having communication with said duct, as and for the purpose set forth, 35 said cap being externally threaded to engage said opening when said bowl is removed.

2. A tobacco pipe, including a stem having a straight central duct therein, an enlarged portion on said stem, said enlarged portion having a threaded laterally extending opening therein communicating with the central duct for removably receiving a bowl, and an end cap threaded externally and internally for reception in the threaded 40 opening when the bowl is removed or over the free extremity of the stem when the bowl is applied.

In testimony whereof I affix my signature in presence of two witnesses.

JOSEPH YARTIN.
